DESIGN FOR A CHARM OR THE LIKE

Melvin Jones, Chicago, Ill., assignor to International Association of Lions Clubs, Chicago, Ill., a corporation of Illinois

Application July 7, 1944, Serial No. 114,334

Term of patent 14 years

(Cl. D45—17)

To all whom it may concern:

Be it known that I, Melvin Jones, a citizen of the United States, residing at Chicago, in the county of Cook and State of Illinois, have invented a new, original, and ornamental Design for a Charm or the like, of which the following is a specification, reference being had to the accompanying drawing, forming a part thereof.

Fig. 1 is a front elevational view of a charm or the like showing my new design; and

Fig. 2 is a side elevation of the same.

I claim:

The ornamental design for a charm or the like, as shown.

MELVIN JONES.
